UNITED STATES PATENT OFFICE.

LAWRENCE L. FOSBURGH, OF SAPULPA, OKLAHOMA.

AEROPLANE.

1,224,915.

Specification of Letters Patent.

Patented May 8, 1917.

Application filed March 4, 1915. Serial No. 12,095.

To all whom it may concern:

Be it known that I, LAWRENCE L. FOSBURGH, a citizen of the United States, residing at Sapulpa, in the county of Creek and State of Oklahoma, have invented certain new and useful Improvements in Aeroplanes, of which the following is a specification.

My invention relates to aeroplanes and 10 more particularly to a device for stabilizing the machine during its course of flight.

The primary object of my invention resides in an improved carrying platform suspended from the frame of a machine, the 15 platform constituting a suitable pendulum and having associated therewith the connecting means of the balancing planes which are movably mounted intermediate the main planes and arranged so as to be acted upon 20 simultaneously when the platform moves in various directions, due to the main planes taking a sudden endwise dip during the flight of the machine.

Another object of my invention resides 25 in the improved means for suspending the platform between the planes.

A further object of my invention resides in the provision of novel flexible means for connecting the platform to the main planes 30 as well as novel locking means associated with the connecting means whereby the balancing planes may be prevented from operating, when desired.

A still further object of my invention 35 resides in the construction of the platform and further in an improved means for maintaining the propeller thereon.

A still further object of my invention resides in the provision of a device of the character described that is simple in construction, efficient in operation and one that can be manufactured and placed on the market 40 at a minimum cost.

Other objects as well as the nature, characteristic features and scope of my invention 45 will be more readily understood from the following description taken in connection with the accompanying drawings and pointed out in the claims forming a part of 50 this specification.

In the drawings:

Figure 1 is a perspective of the invention; 55 Fig. 2 is a longitudinal section of the invention;

Fig. 3 is an enlarged fragmentary per-

spective of the platform showing the locking means; and

Fig. 4 is an enlarged fragmentary perspective of the flexible connecting means between the balancing planes and the platform.

Referring more particularly to the drawing, I provide an aeroplane, preferably of a biplane type including an upper plane 1 and a lower plane 2 suitably connected by means of vertical rods 3, the latter being positioned and rigidly secured adjacent the respective corners of the planes and also adjacent the corners of the substantial square opening 4 provided at a point approximately intermediate the ends of the lower plane 2. Disposed on the under surface of the top plane 1 at a point intermediate the ends thereof is a bar 5, curved fore and aft in order to conform to the under surface of the transversely curved plane, the said bar being supported in this position by means of rods 6, the respective ends of which are rigidly connected to the lower plane adjacent the rods 3, at the opening 4 and to the bar 5 at the respective ends thereof. Pivotally mounted by means of suitable fastening devices 7 on the respective ends of the bar 5 are substantially V-shaped supporting members 8, the fastening devices extending through the members at the vertices thereof. A platform 9 is rigidly connected to the terminals of the V-shaped supporting members. Wheels 10 are rotatably mounted on the longitudinally extending rods 11 carried on the under surface of the platform and serve as a suitable means for facilitating the moving of the machine when it is not in flight. Suitable braces 12 are connected to the longitudinal bars 11 and the supporting members 8 for facilitating the bracing of the parts.

In order to propel the aeroplane, I have provided a rectangular frame 13 and associated the same with the V-shaped supporting members 8 at a point approximately intermediate the planes 1 and 2. A shaft 14 is rotatably mounted in suitable journals 15 mounted on the transverse sides of the frame 13. A propeller 15 is rigidly mounted on the rearwardly projecting end of the shaft. In order to rotate the shaft and consequently rotate the propeller, I provide the shaft with a suitable wheel 16 about which is trained a belt 17, the belt being also asso-

ciated with a gasoline engine 18 carried by the frame 9, the engine being positioned on one side of the latter.

Disposed intermediate the upper plane 1 and the lower plane 2 and upon each side of the opening 4 are balancing planes 19 and 20, the said planes being pivotally mounted, preferably by means of hinges 21 to the forward of the bars 3 and are adapted for 10 swinging movement between the planes 1 and 2. Suitable means have been provided in order to normally hold these balancing planes in a position substantially intermediate the upper and lower planes 1 and 2 and 15 to accomplish this purpose, I have connected one end of a cable 22 to the balancing plane 19 at a point on the upper surface adjacent the free outer corner thereof and trained the cable about a plurality of pulley 20 wheels 23 suspended from the lower surface of the upper plane 1, the opposite end of the cable 22 being rigidly connected to the other balancing plane 20 at a point adjacent the upper outer corner thereof. This 25 cable 22, although movable, tends at all times to maintain the planes in the proper position. In order to further aid in the maintenance of these planes 19 and 20 in this position, I have provided another cable 30 24, the respective ends of which are connected in eyelets 25 adjacent the free inner corners of the balancing planes 19 and 20, said cable being also trained about the intermediate pulley wheels 23 in a manner as 35 shown to advantage in the drawing.

In order to simultaneously act upon these balancing planes and cause the same to move in the event that the aeroplane takes a sudden endwise tip, I have provided a 40 cable 26, one end of which is rigidly connected in any suitable manner to the under surface of the balancing plane 19 adjacent the free outer corner thereof, said cable extending downwardly and being trained 45 about a pulley wheel 27 carried on the upper surface of the lower plane adjacent an outer end thereof and thence extended across the lower plane to another pulley wheel 28 adjacent the opening 4 in the plane. The 50 cable 26 is now extended across the opening 4 and trained about a pulley wheel 29 on the opposite side of the opening and is wrapped about the longitudinally extending rod 30, the rod being rigidly mounted on the trans- 55 verse bars 31 carried by the supporting members 8 at points substantially intermediate the ends thereof and beneath the rectangular frame 13. The cable 26 is now extended to the opposite side of the opening 60 and trained about a pulley wheel 32 carried on the upper surface of the lower plane adjacent the pulley wheel 28. Finally the cable is again extended across the opening 4 and trained about the pulley wheels 32 65 and 33 carried on the upper surface of the

lower plane and positioned respectively adjacent the opening 4 and the free corner of the plane, whereupon it is connected to the under surface of the balancing plane 20 adjacent the outer free corner thereof. By 75 the arrangement of this cable, the respective ends of which are connected to the balancing planes 19 and 20, when the machine takes a sudden or endwise dip to one side, the platform will remain at a substantially perpendicular position with respect to the frame of the machine and because of the cable will exert a pull on the balancing plane on the opposite side from which the machine dips, therefore causing the said plane to be swung downwardly against the atmosphere and consequently causing the balancing plane that is on the other side of the platform to swing upwardly against the atmosphere thus causing the machine to be 85 automatically righted. To further assist in the operation of the balancing planes cables 26 have their upper ends rigidly connected adjacent the free inner corners of the balancing planes, the opposite ends being 90 trained about the pulley wheels 32 and 32 and finally connected to the cable 26 as illustrated to advantage in Fig. 4.

In order to removably lock the balancing planes in various adjusted positions, I have provided a suitable governing means which in this instance consists essentially of a shaft 34, the respective ends of which are rotatably mounted in supporting brackets 35 carried on the upper surface of the platform 95 on the side opposite from that on which the engine is disposed, the said shaft having cables 36 and 37 wrapped thereabout a suitable number of times, the respective ends of which are secured to the under surfaces of 100 the lower plane adjacent the sides of the opening 4 and when the planes are tilted the cables operate about the shaft. Suitably spaced collars 38 are carried by the shafts and serving a suitable means for limiting 105 the movement of the cables on the shaft. Further associated with this locking means and co-operating with the cables 36 and 37 for holding the platform 9 in a suitable rigid position with respect to the planes 1 110 and 2, is my improved operating means which in this instance consists essentially of a hand lever 39 pivotally mounted at its lower end to a bracket 40. A brake shoe 41 is connected to the lever and is adapted for 115 engagement with the wheel 42 rigidly carried on the shaft 34 by means of a suitable elastic element preferably a coil spring 43, the free ends of which are connected to the lever 39 and a part of one bracket 35 so as 120 to normally exert a tension on the shoe and cause the latter to frictionally engage the wheel to prevent rotation thereof. A seg- 125 mental rack 44 is arranged adjacent the lever, the teeth of the rack being at times en- 130

engaged by a manually operable pawl 45 associated with the lever for holding the shoe 41 out of engagement with the wheel 42 when the machine is in flight to permit of the actuation of the balancing planes.

A driver's seat 47 is rigidly mounted on the upper forward surface of the platform 9 adjacent the lever 39 so that the operator of the machine may have ready access to the controlling means.

The operation of my invention is as follows.

Assuming that the machine has been assembled in the manner described and that the same has just begun its course of flight through the atmosphere, the operator disengages the brake shoe 41 from the wheel 42 to permit of the swinging movement of the carriage 9. Should the machine take a sudden endwise dip in either direction, the platform 9, through the force of gravity would be readily swung in the direction of fall, and because of the connection of the cables 22, 24 and 26 with the balancing planes, main planes and platform, it will be apparent that the balancing planes will swing in the proper direction to automatically right the machine simultaneously with the movement of the platform. Should it be desired to maintain the carriage in a substantially rigid relation it is only necessary to actuate the pawl 45 to permit the spring to hold the brake shoe 41 in engagement with the wheel 42 to prevent rotation of the shaft 34.

Although I have shown and described the preferred embodiment of my invention, I desire to be understood that I am not to be limited to the exact details shown, however, great stress is laid upon the swinging platform peculiarly mounted and associated with the main planes and further connected with the balancing planes to automatically actuate the same to righten the machine when it takes a sudden endwise dip. Attention is also called to the novel means for holding the machine in a substantially rigid position when in the air or when it is desired to dispense with the stabilizing device.

From the above description taken in connection with the accompanying drawings, it can easily be seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general and preferred embodiment of my invention and that various minor changes in detail of construction, proportion and arrangement of the parts may be made within the scope of the claims without sacrificing any of the advantages of my invention.

Having thus fully described my invention, what I claim as new and desire to secure by Letters Patent, is:

1. An aeroplane including main planes, balancing planes movably mounted therebetween, a swinging platform associated with the upper main plane, flexible connecting means between the balancing planes and the upper main plane, other flexible means connecting the balancing planes the lower main plane and platform and arranged so that movement of the platform will actuate the balancing planes, a shaft rotatably mounted on the platform, cables having their respective ends connected to the lower main plane and their intermediate portions wrapped about the shaft, and a brake lever removably associated with the shaft for locking the shaft against rotation to consequently prevent actuation of the balancing planes.

2. An aeroplane including upper and lower supporting planes, means for bracing the planes, a bar associated with the under surface of the upper plane, the lower plane being provided with an opening, a platform arranged beneath the opening, supporting members connected to the ends of the platform and pivoted to the bar, a propelling shaft rotatably associated with the members, means on the platform for imparting a rotary motion to the shaft to consequently propel the aeroplane, balancing planes mounted to swing between the main planes, flexible means for connecting the balancing planes with the upper planes, flexible means for connecting the balancing planes with the platform, another shaft rotatably mounted on the platform, cables having the free respective ends connected to the lower main plane and having their intermediate portions wrapped about the last mentioned shaft, a brake lever, means for holding the lever in engagement with the shaft for preventing actuation of the shaft, and means for removably holding the lever out of engagement with the shaft to permit of actuation of the balancing planes.

3. An aeroplane including upper and lower supporting planes, means for bracing the planes, a bar associated with the under surface of the upper plane, the lower plane being provided with an opening intermediate its ends, a platform, supporting means pivotally connected to the bar and arranged through the opening in the lower plane and connected to the platform for supporting the platform beneath the opening in the lower plane, a propeller operatively associated with the supporting means, means on the platform for actuating the propeller, balancing planes pivotally mounted and arranged to swing between the main planes, a cable movably connected

to the upper main plane and having its respective ends connected to the outer ends of the balancing planes, another cable movably mounted on the supporting means and 5 the lower main plane and having its respective ends connected to the outer ends of the balancing planes whereby when the platform is moved the balancing planes will be actuated, flexible means arranged 10 between the lower main plane and the plat-

form, and means mounted on the platform and co-acting with the flexible means for preventing actuation of the balancing planes.

In testimony whereof I affix my signature in presence of two witnesses.

LAWRENCE L. FOSBURGH.
